UNITED STATES PATENT OFFICE.

ARTHUR WARD HAYES, OF LOUISVILLE, KENTUCKY.

POCKET-RECORDER FOR EXPENSE-ACCOUNTS.

991,300.

Specification of Letters Patent.

Patented May 2, 1911.

Application filed June 15, 1908, Serial No. 438,682. Renewed August 20, 1910. Serial No. 578,247.

To all whom it may concern:

Be it known that I, ARTHUR W. HAYES, a citizen of the United States, residing at Louisville, in the county of Jefferson and State of Kentucky, have invented a new and useful Pocket-Recorder for Expense-Accounts, of which the following is a specification.

This invention relates to pocket recorders for expense accounts, and the objects of my improvement are, to provide a pocket recorder for expense or other accounts which shall be simple in construction and efficient in operation.

From years of experience, I know there has been a demand especially among the traveling public, for a more satisfactory method of keeping a detail record of their personal and business expenses. Very few expense accounts are correct, from the fact that a portion of this account is generally made up from memory. There are times when it is not policy to make a note of an expenditure in a book, such as treating, etc. For the above reasons, I have invented an expense recorder which gives, not only a printed detail statement of all expenses, but also classifies these expenses. In addition to this, my device will give a total of the itemized expenses, which can be read at a glance at any time during the day, week, or month, thus making it possible to balance cash on hand at any time without disturbing the weekly or monthly itemized statement.

My invention is very quick in operation, and after familiarity with its use is attained, can be operated without being removed from the pocket. The means for making the daily record is so arranged that it can be spaced daily, thus separating each day's expenditures from those of the previous day, making it possible to know, not only the amount of expenditure, and for what purpose, but also the date thereof.

These objects and advantages I attain by means of the mechanism illustrated in the accompanying drawings, in which—

Figure 1 is a front view; Fig. 2 is an edge view; Fig. 3 is an enlarged back view, with the cover and back plate removed, showing the recording elements at zero position; Fig. 4 is a back view with the cover and back

plate removed, showing the parts set to record an amount, and the printing mechanism in action; Fig. 5 is a vertical transverse section, on the line A—B of Fig. 1, looking to the left, and with the lid partly open; Fig. 6 is a vertical transverse section, on the line A—B of Fig. 1, looking to the right; and Fig. 7 is a front view showing the lid open.

In carrying out my invention I provide an inclosing case 1, preferably in the shape of a watch case, with a hinged lid or cover 2. The operating parts I prefer to arrange in a cup shaped container 3, that can be removed from the case 1, allowing free access to the entire mechanism. The printing mechanism I prefer to attach to the lid 2, in order that it may be readily accessible. Around the inner surface of the rim or cup 3 I arrange a group of annular slides 4—8, in number corresponding to the capacity of the device. An annular slide is provided for each period, that is, cents, dimes, dollars, etc., of the amount it is possible to record, and an additional slide bearing characters for indicating the account to which the amount recorded is chargeable. For the purpose of this description, the annular slides 4—7, intended to register and record amounts, will be referred to collectively as numeral slides and individually as cent, dime, dollar and ten-dollar slides. The annular slide intended for recording characters indicating the account to which the recorded item is chargeable will be referred to as the item slide. In the drawings, 4 refers to the cent slide, 5 to the dime slide, 6 to the dollar slide, 7 to the ten-dollar slide, and 8 to the item slide. The slides 4—8 are divided into four arcuate sections. The sections of the first series beginning at the stem and proceeding clockwise (Fig. 7) and contra-clockwise (Figs. 3 and 4) are disposed concentric with the rim of the case, and are provided with teeth, 9, thus forming a section of crown gear. Pinions 10—14 are provided which mesh with the crown gear sections 9. Pinions 10—14 are secured to the inner ends of sleeves 15—19, on the outer ends of which are flanges, 20—24, having characters on the edges thereof corresponding to the characters to be recorded. The annular slides are operated by means of the

flanges 20—24, through sleeves 15—19, pinions 10—14, and crown gears 9, into position to record the desired character.

The numeral slides are held in position 5 against movement when in zero position, or in a position to make a record, by means of dogs, 25—28, that pivot on a post, 29, and the point of which, 30 engages between teeth, 32, on the second section of the numeral slides. The dogs 25—28 are offset, as shown clearly in Fig. 5, so that a heel, 31, of a dog rests on one slide while the point, 30, engages another of the next lower denomination. That is, the dog 25, resting 10 on the dime slide, locks the cent slide; and the dog 26, resting on the dollar slide, locks the dime slide; the dog 27, resting on the ten dollar slide, locks the dollar slide; the dog 28 resting on the item slide, locks the 15 ten dollar slide. The dogs 26—27—28 have pins, 33, that extend over the dogs of the next lower denomination respectively, that is, the pin in dog 28 extends over dog 27; and the pin in dog 27 extends over dog 26, 20 and so on. The movement of any slide of higher denomination than the dime slide will, by raising the heel 31 of the dog resting on it, depress the point 30 and lock the slide of next lower denomination, and, 25 through pin 33, depress the dog over the next slide of lower denomination, thus locking all slides of lower denomination. When in the zero position, an elevated portion 34, on the item slide 8, raises the heel 31 of dog 28, depressing the point 30, and through pins 33 brings points 30, on dogs 27—26—25, into teeth 32 on the numeral slides, thus locking all of them. It will thus be seen 30 that the numeral slides are locked in the zero position as long as the item slide remains in the zero position. The first tooth 35 of the series of locking teeth 32, on the numeral slides, is omitted, leaving a space, 33, that the heel of the locking dog, pivoted above that slide, may drop into if not prevented by other means.

From the foregoing it will be perceived 40 that the numeral slides are normally locked in the zero position. When the item slide is advanced, by means of flange 20, sleeve 15 and pinion 10, it will remove the elevated portion 34 of the item slide 8 from under heel 31 of dog 28, allowing the dog to drop, raising point 30 and pin 33, and thus freeing 45 all the locking dogs. Any numeral slide may now be moved to recording position. To set up a number to record it will be necessary to set the lowest denomination first. If it is desired to record \$5.25, the cent 50 slide must first be moved to 5, the dime slide to 2, then the dollar slide to 5. If, on the contrary, the dollar slide were first moved to 5, the cent slide and dime slide would be locked and could not be moved without first 55 returning the dollar slide to zero. To the

third series of sections of the annular slides are attached segments, 36, facing the center, on which are provided raised characters or type from which the record is made. The base plate, 37, of the printing mechanism 70 has a central vertical slot, 38, through which screws, 39—40, extend, to hold the plate in movable relation to the lid 2. A post, 41, is provided, adapted to carry a spool of paper, 42. A bracket, 43, has attached to it a platen, 44. A spool, 47, adapted to receive a web of paper, is mounted on a post, 45, provided with a ratchet wheel, 46. A lever, 48, pivoted at 49, has an ink roller, 50, mounted on its lower end, and a pawl, 51, on its upper end adapted to engage the ratchet wheel 46. The pawl 52 serves to prevent backward movement of ratchet wheel 46. A bracket, 53, is secured to the upper part of base plate 37 and lies in the path 85 of plunger 75, when the lid is closed. A spring, 54, serves to keep plate 37 at the upward limit of its movement. The web of paper 55 is brought down from spool 42, under platen 44, and up to the spool 47. 90

The fourth series of sections of the numeral slides have gear teeth, 56, thus forming sections of internal gears to actuate a registering or totaling device. The registering or totaling device in itself forms no 95 part of my invention, as any of the well known devices may be used, I prefer to use the simple one shown in the drawings. Number wheels 57, and attached pinions 58, are mounted in a frame, 60. Springs, 61, 100 are fastened to the frame 60 and bear on pinions 58. The frame 60 is mounted to swing on an eccentric, 62, and is provided with a slot, 63, in an arm, 64, at right angles to the body of the frame. A lever, 65, has 105 a tooth, 66, which enters slot 63. The opposite end, 67, of lever 65, drops into a depression, 68, on the item slide 8, when the same is at zero position, and rides on an elevated portion of the slide, 69, when the 110 slide is moved to recording position. The eccentric 62 pivots on a pin, 70. An arm, 71, is attached to eccentric 62 and has at its opposite end a link, 72, which, in turn, is provided with a finger, 73, adapted to engage a pin, 74, on plunger 75, and a finger, 76, adapted to engage the end of item slide 8 (Fig. 7). A post, 77, serves as a stop to limit the motion of arm 71. A post, 78, serves as a stop for link 72. Moving the 115 arm 71 shifts eccentric 62, and it acts through frame 60 as a lever of the third class, with tooth 66 as the fulcrum, to raise the totaling mechanism out of mesh with internal gear segments 56. Spring 79 is attached to the arm 71 and to frame 60 and aids in raising the frame 60. Spring 79 also retracts the arm 71 when the link 72 is disengaged from pin 74 by the item slide 8 impinging on finger 76. 120

To prepare my recorder for operation, the lid 2 is opened (Fig. 7); a spool of paper is placed on post 41; the end of the paper is passed below platen 44 and attached to spool 47 on post 45; and ink is placed on roller 50. Closing the lid brings bracket 53 and bracket 43 carrying the platen 44 into alinement with stem 75 (Figs. 3 and 4).

The operation of my recorder may be described as follows: Assuming that the parts are in the zero position, as shown in Fig. 3, and that it is desired to register and record an amount spent for railroad fare, and that G is the character chosen to indicate an item chargeable to railroad fare. On attempting to rotate the flanges 20—24 it will be found that only the item flange 20 can be moved. The item flange 20 is rotated until the letter G on the edge thereof is in line with the face of the case. As flange 20 rotates it acts through sleeve 15, pinion 10, and crown gear 9 to advance the item slide 8. The advance of slide 8 causes the following sequence: 1st. Part 34 (Fig. 3) moves from under the heel 31 of dog 28 allowing the heel to drop, raising its pin 33, and freeing the dogs (Figs. 5 and 7) 27—26—25 in succession, thus allowing any of the numeral slides to be moved. 2nd. The letter G, on the type segment 36, is brought into printing position under platen 44. 3rd. The elevated portion 69 of the item slide 8 raises the end 67 of lever 65; tooth 66 pushes arm 64 upward; frame 60 is swung on eccentric 62; and pinions 58 of the totaling device are thrown into mesh with the internal gear segments 56 on the numeral slides. If the railroad fare amounted to \$5.25, the cent flange 24 would be rotated to bring the character 5, on the edge thereof, in line with the character G. As flange 24 rotates it acts through sleeve 19, pinion 14, and gear 9, to advance the cent slide 4 five points, registering 5 on the units wheel of the totaling device and bringing the character 5, on the type segment 36 into printing position under the platen. The dime flange 23 is then rotated to bring the character 2, on the edge thereof, into alinement with the character 5 and the character G already set up. As flange 23 rotates it acts through sleeve 18, pinion 13, and gear 9 to advance the dime slide 5 two points, registering 2 on the tens wheel of the totaling device and bringing the character 2, on the type segment 36, into printing position. As dime slide 5 advances it raises its heel 31 (Fig. 7) of dog 25, depressing its point 30 into the locking-teeth 32 on the cent slide 4, locking the cent slide in position. The dollar flange 22 is then rotated to bring the character 5 on the edge thereof into alinement with the character G and characters 5 and 2 already set up. As dollar flange 22 rotates it acts through sleeve 17, pinion 12 and its crown gear 9 to advance the dollar slide 6 five

points, registering 5 on the dollar wheel of the totaling device and bringing the character 5, on its type segment 36, into printing position. As dollar slide 6 advances it raises the heel 31 of dog 26, depressing its point 31 into the teeth 32 of the dime slide 5, locking it in position. The amount spent having now been registered on the totaling device and set up on the type segments for record, the printed record is made by depressing stem 75 by means of head 80, causing the stem to impinge on the bracket 53, attached to base plate 37, and forcing the printing mechanism downward upon the type. As the plate 37 descends, the ink roller 50 comes into contact with the type set up for record, inking them. When the ink roller 50 moves over the type, the lever 48, to which it is attached, is actuated, and, by means of the pawl 51, advances the ratchet wheel 46 one point and with it the spool 47, winding the printed web of paper onto spool 47 and presenting a fresh surface of paper under platen 44. The continued movement downward of the plate 37 brings the paper 55, which rests against the face of the platen, into contact with the type, in this case "G5.25," set up on the type segments for record, printing said characters on the web of paper. When the pressure is removed from the stem head 80, spring 54 returns the printing mechanism to its normal position. As the printing mechanism returns to its normal position stem 75 rises with it. As stem 75 rises, pin 74 thereon engages the finger 73 on link 72, raising arm 71 and, through the action of eccentric 62, as heretofore explained, raises the totaling mechanism from engagement with the numeral slides. There being now no restraining means, the numeral slides are automatically returned to their zero position by the springs 81, the springs 81 being secured at one end to the slides and at the other to the container 3. The item slide 8 must be returned to the zero position manually, by means of the flange 20. On its return to zero position its end strikes the finger 76 of link 72, pushing it off of pin 74 on stem 75, and spring 79 pulls arm 71 down, until it strikes post 78. The movement of arm 71 shifts the eccentric 62 and, acting on the frame 60 as a lever of the third class, lowers the totaling mechanism to a position in which the lever 65 can throw the pinions 58 into mesh with teeth 56, as described.

In Fig. 1 I show what I have termed a finder, 82. This is an opening in the lid, through which may be seen the character stamped on the back of the crown gear section 9 of the annular slides corresponding to the type on the type segments 36 and the characters on the flanges 20—24, thus making it easy to observe what amount has been set up for record. In Fig. 2 I show an open-

ing 83 through which the total on the total-
ing device may be seen.

Operating the printing mechanism, without
registering and setting up an amount,
will print a row of ciphers across the web
of paper. By doing this the record of each
day's expenses may be kept separate from
that of the previous day.

Having thus described my invention so
that any one skilled in the art pertaining
thereto may make and use it, I claim—

1. In a pocket recorder for expense ac-
counts, a case, a total-registering device,
slides for actuating the same, means for ac-
tuating said slides, characters on said slides
from which a record may be made of the
amount registered, and means for printing
such record.

2. In a pocket recorder for expense ac-
counts, a case, a total-registering device, an-
nular slides for actuating the same, means
extending externally of said case for oper-
ating said slides, characters borne by said
slides from which a record may be made of
the amount registered, and printing mecha-
nism for making such record.

3. In a pocket recorder for accounts, a
case, a total-registering device, annular slides
for actuating the same means for actuating
said annular slides, means for engaging and
disengaging the total-registering device with
said slides, means for locking said slides in
nonoperative and operative position, char-
acters borne by said slides from which a
record may be made, and printing mecha-
nism for making such record.

4. In a pocket recorder for expense ac-
counts, a watch-like case, a total-registering
device, a slide arranged around the inner
wall of said case and adapted to operate said
total-registering device, and means extend-
ing externally of said case for operating said
slide.

5. In a pocket recorder for expense ac-
counts, a watch-like case, a total-registering
device, a slide arranged around the inner
wall of said case and adapted to operate
said total-registering device, and revolute
means extending externally of said case for
operating said slide.

6. In a pocket recorder for expense ac-
counts, a watch-like case, a total-registering
device, a series of slides arranged around the
inner wall of said case and adapted to op-
erate said total-registering device, and means
extending externally of said case for oper-
ating said slides.

7. In a pocket recorder for expense ac-
counts, a watch-like case, a total-registering
device, a series of slides arranged around the
inner wall of said case and adapted to op-
erate said total-registering device, and revo-
lute means extending externally of said case
for operating said slides.

8. In a pocket recorder for expense ac-
counts, a watch-like case, a total-registering
device, means for operating said total-regis-
tering device, a slide arranged around the
inner wall of said case and adapted to en-
gage said total-registering device with said
operating means, and means extending ex-
ternally of said case for operating said slide.

9. In a pocket recorder for expense ac-
counts, a watch-like case, a total-registering
device, means for operating said total-regis-
tering device, a slide arranged around the
inner wall of said case and adapted to en-
gage said total-registering device with said
operating means, and revolute means ex-
tending externally of said case for operating
said slide.

10. In a pocket recorder for expense ac-
counts, a watch-like case, a total-registering
device, a series of annular slides arranged
around the inner wall of said case, one of
said annular slides adapted to engage the
total-registering device with the other an-
nular slides, and means extending externally
of said case for operating said slides.

11. In a pocket recorder for expense ac-
counts, a watch-like case, a total-registering
device, a series of annular slides arranged
around the inner wall of said case, one of
said annular slides adapted to engage the
total-registering device with the other an-
nular slides, and revolute means extending
externally of said case for operating said
slides.

12. In a pocket recorder for expense ac-
counts, a watch-like case, a total-registering
device, means for operating said total-regis-
tering device, a slide arranged around the
inner wall of said case and adapted to en-
gage said total-registering device with said
operating means, means extending externally
of said case for operating said slide, and
means for disengaging said total-registering
device from said operating means.

13. In a pocket recorder for expense ac-
counts, a watch-like case, a total-registering
device, means for operating said total-regis-
tering device, a slide arranged around the
inner wall of said case and adapted to en-
gage said total-registering device with said
operating means, revolute means extending
externally of said case for operating said
slide, and means extending externally of said
case for disengaging said total-registering
device from said operating means.

14. In a pocket recorder for expense ac-
counts, a watch-like case, a total-registering
device, a slide arranged around the inner
wall of said case and adapted to operate said
total-registering device, characters on said
slide representative of the amount registered,
and means extending externally of said case
for operating said slide.

15. In a pocket recorder for expense ac-

- counts, a watch-like case, a total-registering device, a series of slides arranged around the inner wall of said case and adapted to operate said total-registering device, characters on said slides representative of the amount registered, and means extending externally of said case for operating said slides. 65
16. In a pocket recorder for expense accounts, a watch-like case, operating means extending through the stem of said watch-like case, a total-registering device, and an annular slide operatively connecting said operating means and said total-registering device. 70
17. In a pocket recorder for expense accounts, a watch-like case, a sleeve extending through the stem of said watch-like case, a total-registering device, and an annular slide operatively connecting said sleeve and said total-registering device. 75
18. In a pocket recorder for expense accounts, a watch-like case, a series of concentrically arranged sleeves extending through the stem of said watch-like case, a total-registering device, a series of annular slides operatively connecting said sleeves and said total-registering device. 80
19. In a pocket recorder for expense accounts, a watch-like case, a series of concentrically arranged sleeves extending through the stem of said watch-like case, a total-registering device, a series of annular slides operatively connected with said sleeves, a total-registering device, one of said annular slides adapted to engage said total-registering device with the others of said series of annular slides. 85
20. In a pocket recorder for expense accounts, a watch-like case, a series of concentrically arranged sleeves extending through the stem of said watch-like case, a series of annular slides operatively connected with said sleeves, a total-registering device, one of said annular slides adapted to engage said total-registering device with the others of said series of annular slides. 90
21. In a pocket recorder for expense accounts, a watch-like case, a series of concentrically arranged sleeves, a total-registering device, a series of annular slides operatively connected with said sleeves, a total-registering device, one of said annular slides adapted to engage said total-registering device with the other of said series of annular slides, and means extending externally the case for disengaging said total-registering device from said series of annular slides. 95
22. In a pocket recorder for expense accounts, a watch-like case, a sleeve extending through the stem of said watch-like case, 100
- operating means on the outer end of said sleeve, a gear wheel on the inner end of said sleeve, a total-registering device, an annular slide adapted at one point to mesh with said gear wheel and at another point to operate said total-registering device. 105
23. In a pocket recorder for expense accounts, a watch-like case, a series of concentrically arranged sleeves extending through the stem of said watch-like case, operative means on the outer end of each sleeve, a gear wheel on the inner end of each sleeve, a series of annular slides each adapted to mesh with a corresponding gear wheel and be operatively engaged by a total-registering device. 110
24. In a pocket recorder for expense accounts, a watch-like case, a series of concentrically arranged sleeves extending through the stem of said watch-like case, operative means on the outer end of each sleeve, a gear wheel on the inner end of each sleeve, a series of annular slides each adapted to mesh with a corresponding gear wheel, one of said annular slides adapted to engage a total-registering device with the others of said series of annular slides. 115
25. In a pocket recorder for expense accounts, a watch-like case, a series of sleeves concentrically arranged around a central plunger and extending through the stem of said watch-like case. 120
26. In a pocket recorder for expense accounts, a watch-like case, a series of sleeves concentrically arranged around a central plunger and extending through the stem of said watch-like case, said sleeves having flanges on the outer ends and gear wheels on the inner ends thereof, and a head on the outer end of said central plunger. 125
27. In a pocket recorder for expense accounts, a watch-like case, a series of sleeves concentrically arranged around a central plunger and extending through the stem of said watch-like case, said sleeves having gear wheels on the inner ends thereof and flanges, of varying diameter on the outer ends thereof. 130
28. In a pocket recorder for expense accounts, a watch-like case, a series of sleeves of varying lengths concentrically arranged around a central plunger and extending through the stem of said watch-like case, gear wheels on the inner ends of said sleeves and flanges of varying diameter on the outer ends thereof. 135
29. In a pocket recorder for expense accounts, a watch-like case, a series of sleeves of varying lengths concentrically arranged around a central plunger and extending through the stem of said watch-like case, gear wheels on the inner ends of said sleeves and flanges of varying diameter on the outer ends thereof, a head on the outer end of said 140

- central plunger and operative means attached to the portion of said central plunger within said watch-like case.
30. In a pocket recorder for expense accounts, a watch-like case, an annular slide disposed around the inner wall of said case, said annular slide comprising a series of sections, three of said sections being adapted to engage respectively operating, locking, and registering means, a fourth section being provided with characters from which a record may be printed.
31. In a pocket recorder for expense accounts, a watch-like case, an annular slide disposed around the inner wall of said case, said slide comprising a series of sections provided successively with gear teeth, locking teeth, printing characters, and gear teeth.
- 20 32. In a pocket recorder for expense accounts, a watch-like case, a series of annular slides disposed around the inner wall of said case, each of said slides comprising a series of sections provided successively with gear teeth, locking teeth, printing characters and gear teeth.
- 25 33. In a pocket recorder for expense accounts, a watch-like case, an annular slide disposed around the inner wall of said case, comprising successively a section provided with gear teeth, a short elevated locking section, a plain depressed section, a section provided with printing characters, a short
- 30 section with depressed surface, and a section having a surface raised relative to said short depressed section.
34. In a pocket recorder for expense accounts, a watch-like case, a series of annular slides, locking means comprising a series of dogs, each of said dogs so offset that the heel rests on one slide and the point engages an adjoining slide.
35. In a pocket recorder for expense accounts, a watch-like case, a series of annular slides, locking means comprising a series of dogs, each of said dogs so offset that the heel rests on one slide and the point engages an adjoining slide, said dogs each provided with a projection on one side extending over the point of the adjoining dog.
36. In a pocket recorder for expense accounts, a watch-like case, printing mechanism slidably secured to the lid of said case, and adapted when said lid is closed to be brought into operative position.
37. In a pocket recorder for expense accounts, a watch-like case, printing mechanism comprising a base plate, a post adapted to hold a spool of paper, a platen, a spool adapted to receive a web of paper, an inking roller, and operative means connecting said inking roller and said spool.

ARTHUR WARD HAYES.
